CARDBOARD DISPLAY DEVICE

John V. Horr, Hastings on Hudson, N. Y., assignor to Einson-Freeman Co., Inc., Long Island City, N. Y., a corporation of Delaware

Application August 10, 1937, Serial No. 158,318

13 Claims. (Cl. 40—126)

My present invention relates generally to display devices, and has particular reference to collapsible cardboard displays.

A general object of my invention is to provide a novel type of display structure, presenting to view a multiplicity of display panels arranged in an attractive staggered, zigzag relationship.

A more particular object is to provide a display in which the panels are arranged in superposed tiers, so that by providing for fewer panels in the upper tier or tiers a pyramidal effect can be produced.

A still further object of the invention is to provide a construction which is simple and inexpensive to manufacture, staunch and stable when in set-up condition, yet capable of extremely simple collapsing of the same into a compact, flat condition.

The present device is characterized by the employment of two cardboard blanks, each of which is zigzag in configuration, the blanks being in lazy-tongs interengagement, this interengagement being preferably effected by providing downwardly opening slots in one blank and upwardly opening slots in the other blank, where the blanks intersect.

It is a particular feature of the invention to provide each blank with certain portions of lesser height and other portions of greater height, these portions being so arranged that the low portions of both blanks conjointly define a bottom tier of display panels arranged side-by-side in zigzag relation; while the high portions of both blanks conjointly define an upper tier of display panels arranged side-by-side in zigzag relation.

I achieve the foregoing objects, and such other objects as may hereinafter appear or be pointed out, in the manner illustratively exemplified in the accompanying drawings, wherein—

Figure 1 is a plan view of one of the blanks entering into the present construction;

Figure 2 is a plan view of the second blank;

Figure 3 is a plan view of an illustrative auxiliary panel;

Figure 4 is a perspective view of the blank of Figure 1 in set-up condition;

Figure 5 is a perspective view of the blank of Figure 2 in set-up condition;

Figure 6 is a perspective view of the entire assembled device when set up;

Figure 7 is a cross-sectional view taken substantially along the line 7—7 of Figure 6;

Figure 8 is a view similar to Figure 7, illustrating the manner of collapsing the device;

Figure 9 is a detail cross-sectional view taken substantially along the line 9—9 of Figure 6;

Figure 10 is a view similar to Figure 6, illustrating a modification; and

Figure 11 is a cross-sectional view taken substantially along the line 11—11 of Figure 10.

It will be understood that the blanks entering into the present construction are preferably of conventional cardboard stock, suitably scored and die cut to provide the necessary configuration and fold lines.

The blank of Figure 1 has the substantially straight bottom edge 20, and is shaped to provide the relatively low portions 21, 22, 23, and 24. Between the portions 21 and 22 there is a portion 25 of relatively greater height, and a similar high portion 26 is arranged between the portions 23 and 24.

For purposes presenting to be described, an attachment flap 27 is arranged at the end of the portion 21, and a similar attachment flap 28 is arranged at the end of the portion 24. Downwardly opening slots 29 and 30 are arranged in alignment with the right-hand edges of the high portions 25 and 26. An attachment flap 31 is hingedly arranged on the right-hand edge of the high portion 25, and a slot 32 is provided in alignment with the slot 29. A similar attachment flap 33 is arranged on the left-hand edge of the high portion 26, together with a slot 34 similar to the slot 32. Upwardly projecting tabs 35 and 36 define upwardly opening slots 37 and 38 on the outer edges of the portions 25 and 26.

Score lines, indicated by dot-and-dash lines in Figure 1, are also provided in the blank so as to permit the blank to be set up in the zigzag condition shown most clearly in Figure 4.

The blank of Figure 2, which is complementary with respect to the blank of Figure 1, is also provided with the substantially straight bottom edge 39, with the relatively low panel portions 40, 41, 42, and 43, and with the relatively high portions 44 and 45. Upwardly opening slots 46 and 47 are arranged in alignment with the outer edges of the portions 44 and 45, these slots ultimately interengaging with the slots 29 and 30, respectively, to hold the two blanks in intersecting lazy-tongs interengagement.

Attachment flaps 48 and 49 are arranged on the outer edges of the portions 44 and 45, intended ultimately to cooperate with the slots 32 and 34.

The blank of Figure 2 is also provided with score lines, indicated by dot-and-dash lines, to

permit the blank to be set up into the zigzag condition shown most clearly in Figure 5.

The blank 50 of Figure 3 is an auxiliary panel and is provided with the downwardly opening slots 51 and 52 which are ultimately intended to interengage with the slots 37 and 38.

In the devices illustrated in Figures 1-9, the low portions 22, 23, 40, 41, 42, and 43 are ultimately designed to constitute display panels; and the relatively high portions 25, 26, 44, and 45 are also intended ultimately to serve as display panels. With this object in view, these particular panels or portions may be suitably configured in any desired manner depending upon the purpose for which the display is intended. In the illustrated embodiment, the display is designed to represent a plurality of bottles, and for this reason the upper edges of the enumerated display panels are configured like the upper end of a bottle. Suitable lithography or printing ultimately completes the display, as will be understood by those skilled in the art.

After the blanks of Figures 1, 2, and 3 have been manufactured, as hereinbefore described, the completion of the manufacturing process is accomplished by first folding the panels into the relationships of Figures 4 and 5; then applying the blank of Figure 4 downwardly over the blank of Figure 5 so that the slots 29 and 30 interengage with the slots 46 and 47, respectively; and finally securing the attachment flaps 27 and 28, preferably by means of adhesive, to the outer edges of the panels 40 and 43. This causes an interengagement of the lazy-tongs variety. To complete the interengagement, the high portion 25 must be hingedly connected with the high portion 44, and the high portion 26 must be similarly hinged to the high portion 45. This may be accomplished in the manner illustratively shown most clearly in Figure 9, by inserting the flap 48 through the slot 32 and inserting the flap 49 through the slot 34.

With these two blanks thus interengaged and assembled, the resulting device may be opened up into the display position of Figures 6 and 7, or it may be collapsed into substantially flat, compact relationship, as indicated in Figure 8. It will be understood, however, that Figure 8 does not represent the device in fully collapsed condition, since an even more compact collapsing may be effected when the device is to be shipped, packed, or stored.

One of the outstanding advantages of the present construction lies in the fact that the compacted device of Figure 8, when unwrapped by the ultimate user, requires no manipulations in order to bring it into set-up condition. In fact, the normal springiness of the cardboard blanks tends to expand the device from the condition of Figure 8 to the condition of Figure 7. The user, therefore, even though highly unskilled, can hardly make any mistake in adjusting the device to set-up condition. To help him further, and to brace the device, the auxiliary panel 50 is applied in the manner indicated in Figure 6. Since this panel is arranged in a plane which intersects the planes of the display panels, and since the slots 51 and 52 are thus at a predetermined distance from each other, the engagement of these slots with the slots 37 and 38 necessarily adjusts the entire device to the proper degree of expansion and holds it in such proper set-up condition.

The ultimate effect is obvious from Figure 6. In the illustrated form, a series of six display panels are arranged in side-by-side, zigzag rela-

tionship at the bottom of the device; and above this bottom tier four elevated display panels are arranged in a pleasing zigzag relationship slightly to the rear, serving as an upper tier. The effect is a pyramidal one, and where the panels depict bottles or the like an attractive composite display effect is produced.

The ultimate collapsing of the device for storage or shipment is effected in the reverse manner, by removing the auxiliary panel 50 and collapsing the resultant structure into the relationship of Figure 8.

The invention lends itself readily to modification in the manner illustratively shown in Figures 10 and 11. In this construction, one blank has the relatively low portions 53, 54, 55, 56, and 57, and the relatively high portions 58, 59, and 60. The other blank has the relatively low portions 61, 62, 63, 64, and 65, and the relatively high portions 66, 67, and 68. Where the blanks intersect, interengaging slots are provided as hereinbefore described, and a separable hinging means such as the flap-and-tab arrangement of Figure 9 is provided to connect the portion 66 with the portion 58, the portion 67 with the portion 59, and the portion 68 with the portion 60. Attachment flaps 69 and 70 complete the assembly, and an auxiliary panel may or may not be provided to facilitate the setting-up and to hold the device in properly braced condition.

It will be noticed that in the embodiment of Figure 10 the lower tier has eight display panels while the upper tier has six. In a similar manner, additional panels may be provided, to any desired extent, enlarging the device to suit particular requirements.

In general, it will be understood that changes in the details, herein described and illustrated for the purpose of explaining the nature of my invention, may be made by those skilled in the art without departing from the spirit and scope of the invention as expressed in the appended claims. It is, therefore, intended that these details be interpreted as illustrative, and not in a limiting sense.

Having thus described my invention, and illustrated its use, what I claim as new and desire to secure by Letters Patent is—

1. In a cardboard display device, a pair of zigzag blanks in lazy-tongs interengagement, each blank having portions of lesser height and other portions of greater height, the low portions conjointly defining a continuous bottom tier of display panels arranged side by side in zigzag relation, the high portions conjointly defining a continuous upper tier of display panels arranged side by side in zigzag relation.

2. In a cardboard display device, a pair of zigzag blanks in lazy-tongs interengagement, each blank having portions of lesser height and other portions of greater height, the low portions conjointly defining a bottom tier of display panels arranged side by side in zigzag relation, the high portions conjointly defining an upper tier of display panels arranged side by side in zigzag relation, the total number of display panels in the upper tier being less than the total number in the bottom tier, and the end panels of the bottom tier extending beyond the end display panels of the upper tier thereby producing a pyramidal effect.

3. In a cardboard display device, a pair of zigzag blanks in lazy-tongs interengagement, each blank having portions of lesser height and other portions of greater height, the low por-

tions conjointly defining a continuous bottom tier of display panels arranged side by side in zigzag relation, the high portions conjointly defining a continuous upper tier of display panels arranged side by side in zigzag relation; one blank having downwardly opening slots, the other upwardly opening slots, where the blanks intersect, and said slots interengaging and thereby retaining the blanks in said lazy-tongs interengagement.

4. In a cardboard display device, a pair of zigzag blanks in lazy-tongs interengagement, each blank having portions of lesser height and other portions of greater height, the low portions conjointly defining a bottom tier of display panels arranged side by side in zigzag relation, the high portions conjointly defining an upper tier of display panels arranged side by side in zigzag relation; and means for separably interlocking the high portions of one blank with the high portions of the other.

5. In a cardboard display device, a pair of zigzag blanks in lazy-tongs interengagement, each blank having portions of lesser height and other portions of greater height, the low portions conjointly defining a bottom tier of display panels arranged side by side in zigzag relation, the high portions conjointly defining an upper tier of display panels arranged side by side in zigzag relation, and means hingedly connecting the ends of one blank with the corresponding ends of the other.

6. In a cardboard display device, a pair of zigzag blanks in lazy-tongs interengagement, each blank having portions of lesser height and other portions of greater height, the low portions conjointly defining a bottom tier of display panels arranged side by side in zigzag relation, the high portions conjointly defining an upper tier of display panels arranged side by side in zigzag relation, an auxiliary display panel, and means for removably securing said panel to one of said blanks, said auxiliary panel being arranged to brace the device against lazy-tongs maladjustment.

7. In a cardboard display device, a pair of zigzag blanks in lazy-tongs interengagement, each blank having portions of lesser height and other portions of greater height, the low portions conjointly defining a bottom tier of display panels arranged side by side in zigzag relation, the high portions conjointly defining an upper tier of display panels arranged side by side in zigzag relation, an auxiliary display panel, and means for removably securing said panel to one of said blanks, said auxiliary panel being arranged in a single plane which intersects the planes of said first-named display panels, thereby serving to brace the device against lazy-tongs maladjustment.

8. In a cardboard display device, a pair of zigzag blanks in lazy-tongs interengagement, each blank having portions of lesser height and other portions of greater height, the low portions conjointly defining a bottom tier of display panels arranged side by side in zigzag relation, the high portions conjointly defining an upper tier of display panels arranged side by side in zigzag relation; and means for separably interlocking the high portions of one blank with the high portions of the other, said means being completely concealed behind said high portions.

9. In a cardboard display device, a pair of zigzag blanks in lazy-tongs interengagement, each blank having portions of lesser height and other portions of greater height, the low portions conjointly defining a bottom tier of display panels arranged side by side in zigzag relation, the high portions conjointly defining an upper tier of display panels arranged side by side in zigzag relation; and means for separably interlocking the high portions of one blank in hinged relation to the high portions of the other, thereby permitting complete lazy-tongs collapse of the device.

10. A cardboard display device comprising a pair of zigzag blanks in lazy-tongs interengagement, each blank having portions of lesser height and other portions of greater height, the low portions conjointly defining a continuous bottom tier of display panels arranged side by side in zigzag relation, the high portions conjointly defining a continuous upper tier of display panels arranged side by side in zigzag relation, means for separably interlocking the low portions of said blanks, and means for separably interlocking the high portions of said blanks.

11. In a cardboard display device, a pair of zigzag blanks in lazy-tongs interengagement, each blank having portions of lesser height and other portions of greater height, the low portions conjointly defining a bottom tier of display panels arranged side by side in zigzag relation, the high portions conjointly defining an upper tier of display panels arranged side by side in zigzag relation, means for separably interlocking the low portions of said blanks, and means for separably interlocking the high portions of said blanks; said respective means being in vertical alignment along the meeting edges of adjacent panels.

12. A cardboard display device comprising a pair of zigzag blanks in lazy-tongs interengagement, each blank having portions of lesser height and other portions of greater height, the low portions conjointly defining a continuous bottom tier of display panels arranged side by side in zigzag relation, the high portions conjointly defining a continuous upper tier of display panels arranged side by side in zigzag relation; means for separably interlocking the low portions of one blank in hinged relation to the low portions of the other, and means for separably interlocking the high portions of one blank in hinged relation to the high portions of the other, thereby permitting complete lazy-tongs collapse of the device.

13. In a cardboard display device, a pair of zigzag blanks in lazy-tongs interengagement, each blank having portions of lesser height and other portions of greater height, the low portions conjointly defining a bottom tier of display panels arranged side by side in zigzag relation, the high portions conjointly defining an upper tier of display panels arranged side by side in zigzag relation; means for separably interlocking the low portions of one blank in hinged relation to the low portions of the other, and means for separably interlocking the high portions of one blank in hinged relation to the high portions of the other, said respective means being in hinging alignment, thereby permitting complete lazy-tongs collapse of the device.

JOHN V. HORN.
